LOUD SPEAKER HAVING BALANCED MAGNETIC CIRCUITS

Application filed January 26, 1931. Serial No. 511,152.

Our invention relates to improved types of loud speaker motors, and while it is applicable to motors in which the field flux is furnished by a permanent magnet or magnetic system, the specific embodiment which we shall describe in making a disclosure of my invention, will be a type of motor in which the field is electro-magnetic.

When the principles of operation of our structure are made clear in the ensuing specification, it will be understood that our invention may be embodied in or employed in connection with, a wide variety of loud speaker constructions. The particular construction which we shall describe as exemplary, is a construction made by us in which the parts have been reduced to their simplest form, both from the operating standpoint and from the standpoint of cost.

It has been one of our objects to simplify the construction and decrease the cost of loud speaker motors, and we have succeeded in constructing a motor in accordance with the following disclosure at a commercial cost materially beneath the cost of any other commercial loud speaker of which we are aware. As distinguished from the operative elements of our speaker, certain constructional features of the exemplary commercial embodiment which we shall describe herein are the invention of Ralph H. Langley, and are claimed in his co-pending application Serial No. 509,555, filed Jan. 19, 1931. Fundamentally our invention is addressed, however, to a new principle of loud speaker operation which will be fully explained, and which enables us to construct magnetic reproducers having enhanced efficiency, being free from a number of the well known difficulties hitherto attendant upon speakers of the magnetic armature type, and having substantially all of the advantages hitherto obtained in the popular moving coil type of loud speakers.

The objects of our invention will be set forth in detail hereinafter, or will be entirely apparent to one skilled in the art upon reading these specifications, and reference is now made to the drawings in which:

Figure 1 is a diagrammatic perspective

representation of the parts of the speaker embodying our invention;

Figure 2 is also a diagrammatic representation showing the relationship of the armature and the magnetic bridge portions to the poles of my field structure;

Figure 3 is a diagram in which magnetic flux is plotted against current to show the approach to a condition of magnetic saturation;

Figure 4 is a scale drawing showing in plan one of the laminations of a field element;

Figure 5 is an edgewise view of an assembled field element;

Figure 21 is an end elevation of a completed motor;

Figure 22 is a top plan view of a completed motor;

Figure 23 is a sectional view of a motor taken along the lines 23-23 of Figure 22;

Figure 24 is a side elevation of the completed motor; and

Figure 25 is a sectional view of the motor taken along the lines 25-25 of Figure 24.

One of the objects of our invention has been to produce in a magnetic armature type speaker, a construction in which a return path is provided for the alternating or fluctuating flux in the armature, which path is not co-extensive with the path of the flux and field structure. Accordingly, we have devised, as will fully be explained, a structure in which the return path for the armature flux is in a structure lying essentially in a plane transverse to the plane of the main field structure. As has been understood by investigators in this field, one of the disadvantages of the magnetic type of loud speaker has been the permeation of the field structure by the alternating flux produced in the armature.

Another well known disadvantage of the magnetic type speaker has been the saturation of the armature with the magnetic flux produced by the field, and it has been another object of our invention to produce a magnetic type speaker in which the armature is practically free of magnetic saturation due to the field.

Due in part to the foregoing disadvantage, viz., the saturation of the armature by the field flux, but also affected by other factors, the armature of magnetic type speakers has been less readily able to give satisfactory reproduction of impressed signals because it is in a state of relative unbalance upon movement; that is to say, the closer the armature approaches either pole of the field, the more strongly it is attracted to the said pole, and so great is the increase in this attraction upon movement that the motion-response to the variations in the armature actuation current is no longer true. The response of such a motor is essentially non-rectilinear; and it is an object of our invention to produce, and we have succeeded in producing, a motor the response of which is much more nearly rectilinear.

The essential features of our motor are set forth diagrammatically in Figure 1, wherein we have shown a field structure comprising a core of essentially C shape, and having a back portion 1, side portions or legs 2 and 3, and opposite portions on the opposite ends of these legs which are essentially pole pieces, and may conveniently be called N and S since they will be referred to in this way in Figure 2 in connection with an explanation of the operation of our motor. The pole pieces N and S are separated by a space 4, which is an air-gap in which an armature 5 of strip form may move. It will be understood that this armature is mounted in suitable supports at its ends and is free to vibrate in its central portion, which is the portion located between the pole pieces N and S. A field coil 6 has been indicated diagrammatically as situated upon the back portion of my field core structure. When

this coil is energized by direct current, the field core structure will be magnetized and permeated by a constant flux. It may be so magnetized that the pole pieces marked N and S will be respectively the north and south poles of the magnetic structure, the flux across the air-gap 4 passing through the central portion of the armature 5. We have indicated diagrammatically voice coils 7 and 8 upon the portions of our armature 5 which extend beyond the air-gap. These coils are connected in series, but are wound in the opposite direction so as to have an opposite magnetic effect upon the central portion of the armature. These coils are intended, of course, to be energized by a voice current of fluctuating or alternating character. The passage of this current in one direction will tend to magnetize the armature with a north pole at its center, while the passage of the current in the opposite direction will tend to magnetize the armature with a south pole at its center. A loud speaker motor constructed merely as just described would be operative, but its efficiency would be relatively low because there would not be any closed magnetic circuit for the alternating flux set up in the armature. A feature of our construction is the provision of means for completing the magnetic circuit for the armature flux, and in the preferred embodiment illustrated in Figure 1, we have shown magnetic bridge arms or by-pass path constructions 9, 10, 11 and 12. These arms connect the pole pieces N and S with the outer ends respectively, of the armature. Their function will now be explained more in detail.

I have shown in Figure 2 the pole pieces N and S with the armature 5 lying in the air-gap 4 between them. The armature is connected by a suitable drive rod 13, passing through a perforation 14 in the pole piece N and connecting the armature either directly or through a suitable motion transmitting or converting mechanism to a vibratile device, such as a cone 15. The magnetic arms 9 to 12 inclusive, are shown in elevation, and the voice coils have been indicated at 7a and 8a. When the field structure is actuated by a suitable direct current, there will be a flux in the pole pieces N and S and across the air-gap 4 in the direction of the arrows in Figure 2. The arms 9 to 12 are magnetic arms, and as respects the field flux, the arms 9 and 10 upon the one side and the arms 12 and 11 upon the other act as magnetic by-pass paths for the field flux, and they will be saturated with a magnetic flux in the direction of the arrows. It is our desire to have them saturated as aforesaid, and for this reason they are made of relatively light magnetic material. They may be made of thick material, but the operation of our speaker will not be entirely the same as that

which we shall presently describe; and although good speakers may be made this way, the relationship of parts is very much more exact and hard to obtain than if the paths 5 are made relatively light and are kept substantially saturated. In Figure 3 we have, by way of example, plotted flux against current to produce a curve 16, showing the degree of magnetic saturation in one of our 10 arms. We have found it preferable so to proportion the size of our arms with relation to the size of the field structure and the flux therein, that the arms will be operated at some point high up on the saturation 15 curve, such as the point 17.

In considering the operation of our speaker, the arms 10 and 11 may be first considered. If the coils 7a and 8a are magnetized by a current which tends to produce a 20 north pole at the center of the armature, the direction of the flux in the armature will be that of the small arrows within the ends thereof. A flux flowing inwardly in the left hand end of our armature must take as its 25 return path, the pole piece S and the arm 11. The arm 11 is saturated in the direction of the arrow, and therefore is a low reluctance path. Flux flowing inwardly in the right hand end of our armature must take a path 30 embracing the arm 10 and the pole piece S. The arm 10 is saturated in the direction of the arrow; but the direction of the flux in the armature is opposite to this and therefore can flow in the arm 10 over a relatively 35 low reluctance path opposite in direction to the direction of saturation therein. Thus a magnetic circuit for the armature flux is presented by the right hand end of the armature, the pole piece S and the arm 10. 40 The central portion of the armature is more strongly magnetized as a north pole, and is repelled from the pole piece N and attracted to the pole piece S.

If there were in Figure 2 no arms 10 and 45 12, it is clear that the armature would be permeated and perhaps saturated by the field flux, since there would be a magnetic circuit between the pole pieces N and S comprising in sequence, the arm 9, the armature, 50 and the arm 11. A magnetic speaker of some efficiency can be made in this way, and its operation is vastly improved over that which results when no return paths are provided for the armature flux. The situation 55 which has been described for one direction of the alternating voice coil current will, of course, be reversed for the other alternation; and if the direction of the current in the voice coils 7a and 8a tends to magnetize the 60 armature with a south pole at its center, there will be presented to the armature flux a high reluctance path comprising the arm 11, and a low reluctance path comprising the arm 9.

65 Now, when there is added to this system

the arms 10 and 12 several results are accomplished. Since the arms 9 and 10 on the one side and the arms 12 and 11 on the other form magnetic by-pass paths for that portion of the field flux which they can carry 70 up to their point of saturation, and since the armature is connected between these by-pass paths, there is produced a balanced magnetic bridge circuit, in which the armature is substantially unsaturated by the field flux, in 75 which the production of an alternating flux in the armature is not modified by any substantial resident magnetic permeation in the armature, and in which magnetic circuit return paths for the alternating flux in both ends of the armature are provided. It will be noted also, that the magnetic circuit or circuits for carrying the alternating flux of the armature are in a plane different from the plane of the field core, and that there 80 is substantially no tendency for the field core to carry the alternating flux produced in the armature.

Let it be supposed that the action of the coils 7a and 8a is to produce a north pole 85 at the center of the armature 5 in Figure 2. In accordance with the foregoing explanation, it will be clear that there will be presented to this flux relatively high reluctance return paths comprising arms 9 and 12, and 90 relatively low reluctance return paths comprising arms 10 and 11. Upon the passage of the current in the opposite direction, i. e. so as to magnetize the armature with a south pole at its center, the paths embracing the 95 arms 9 and 12 will be low reluctance paths, and the paths embracing the arms 10 and 11 will be high reluctance paths. Since the flux flows in the low reluctance paths essentially by bucking a saturation flux therein, 100 it will be clear that our construction provides shifting balance points for our armature, lying out upon the several arms. The function of the return paths in strengthening 105 the armature flux will be apparent, and the repulsive and attractive forces acting upon our armature at its central portion will, of course, produce in it the vibrations which are transmitted by the drive rod 13 to the vibratile device 15 in reproducing sound. 110 Our armature is substantially not permeated by the field flux, and its response to fluctuations of the armature current is not only true, but powerful.

Hereinabove we have described our motor 120 as operating with what we have termed a strip form armature with either a pair of magnetic arms connecting the ends of our armature respectively with the pole pieces N and S, or with a plurality of magnetic arms completing the magnetic circuits as 125 shown in Figure 2. We prefer the latter form because we have found that it gives somewhat superior results, but there is another modification which we have also found 130

- to give very nearly as good results, and which has an economical advantage. In this modification, instead of employing a strip form armature, we employ what we have termed a reed form armature, i. e., an armature which is mounted at one end only, the other end being free to vibrate. Such a construction may be understood from Figure 2 if, for example, the magnetic arms 9 and 10 are eliminated, the voice coil 7a taken away, and the armature 4 cut off, say close to the right hand edge of the pole pieces N and S. The armature will then be in the form of a reed mounted at its left hand end between the magnetic arms 11 and 12. It will be magnetized by the voice coil 8, as has been described, and the operation of this modification will be essentially the same as that which has been described for the other modifications. A return path for each of the magnetic fields produced by the fluctuations of the alternating current will comprise respectively, the armature, the magnetic arm 12, and the pole piece N for one path, and the armature, the magnetic arm 11 and the pole piece S for the other path. There is greater necessity in this modification for careful proportioning of the armature, and it will be advisable to provide an armature, where possible, the natural period of which is outside of the audible range. In speakers of the reed type constructed in this way we have secured very excellent results, and very true reproduction.
- We will proceed now to the construction of an exemplary commercial speaker embodying our invention as just described. We have shown in Figure 4 a stamping forming a lamination of our core. For convenience in assembling the motor, as hereinafter to be described, the core is made in two pieces, which are afterward put together to form a completed core. The laminations 18 of Figure 4 are provided with suitable holes and are put together to form the core members 18a of Figures 5 and 6. The laminations may be assembled by means of rivets 19. The front portion N' of the core member 18a may conveniently be made a little wider than the rear portion, as shown, and the perforation 14' may be made therein for the passage of the drive rod. The core member may also be provided with perforations 20 and 21 for purposes presently to be described. For each motor two of these core pieces are employed, only one of which, however, need have the perforation 14'. In the portion marked N', shoulders 22 are provided to hold the voice coils.
- As shown in Figures 7, 8 and 9, bracket members of non-magnetic material are used and are adapted to be attached respectively to the core pieces 18a, and to each other. These brackets may be made of cast aluminum, but other non-magnetic materials will serve. They comprise a body portion having parts 23 and 24 extending at right angles. The part 23 has a flange portion 25, and the part 24 has another flange portion 26. The flange portion 25 may be provided with perforations 21a whereby it may be fastened to one of the core members. A reinforcing rib structure 27 may join the flanges 25 and 26 across the body of the bracket, and this rib structure may be provided with a boss 28 perforated and threaded as at 29 for the reception of a screw in holding the motor to a suitable support. The flange member 26 has a projection 26a upon one end to hold the armature in the magnetic arms. The flange may have perforations 30 for the reception of bolts in assembling the motor. A pair of these brackets is assembled with a core member 18a in such a way that the flange 25 is attached by means of rivets 31, passing through the perforations 21a in the flange and 21 in the core member, the portion N' extending beyond the bracket, as shown in Figure 10, and the flange portions 26a extending out opposite the portion N' and lying in a plane at right angles to the plane of my core piece. The assembly shown in elevation in Figure 11 may be ground, or otherwise dressed, until the faces of the flanges 26 and the ends of the core piece lie in the same plane. In building up the motor, two of the assemblies shown in Figure 11 are fastened together, with the respective flanges 26 contiguous and parallel, and it will be clear that by introducing spacers between the flanges 26, the core members may be spaced to the extent of producing an air-gap of the desired width.
- In Figures 12, 13, and 14, one of the magnetic arm members is shown. It has a body portion 32 and flange portions 33 and 34, one of which is provided with notches 35, and the other with an attachment perforation 36.
- In putting the motor together, two of the assemblies of Figure 11 are positioned in opposite relationship, as aforesaid. This is illustrated in the side elevation of Figure 24 where the opposed flanges 26 are shown attached together, as by bolts 37 and 38. The extensions 26a are shown in opposed relationship, and between them is the armature 5, and the flanges 34 of arms corresponding to the arms 9 and 10 of Figure 2 and indicated by their body portions 32 and 32a. Where fastened by the bolt 38, the flange portions 26a are spaced apart by three thicknesses of metal, namely, the thickness of the armature and the thickness of the flanges 34 of the magnetic arms lying on either side of the armature. Where the armature passes between the pole pieces N' and S' of the core structure, there will be a space on either side of the armature, determined by the thickness of the flanges 34 be-

70

130

tween the flanges 26a of the brackets. Thus, by grinding through the faces of the assemblies shown in Figure 11, the pole spacing is secured with a great degree of accuracy

6 by the simple method just described; and a similar spacing is obtained at the rear end of my core structure by inserting between the two parts, the blocks 39 shown in Figures 23 and 25. It is thought that the general assembly of the motor will be clear from a consideration of the several figures.

10 Figures 19 and 20 illustrate an assembly of the armature 5 and the drive rod 13. The armature has perforations 40 at its

15 ends for the passage of the bolts 38. A field coil structure 6a is shown in the several figures positioned on the rear portion of the core structure. The voice coils are indicated at 7a and 8a, and are illustrated on

20 an enlarged scale in Figures 15 and 16, where it will be seen that in the end flange there is a groove 41. In this construction, the voice coils are held spaced apart by the pole pieces N' and S' in a horizontal direction, and in order that they may not shift, there is an engagement of the ends of the pole pieces in the notches 41; and the shoulders 22 of the pole pieces engage the flanges of the coils so as to hold them rigidly against motion. This will be clear from a consideration of Figure 23.

25 Referring again to Figure 2, the voice coils 7a and 8a are positioned very close to the pole pieces N and S, and separated some distance from the point of attachment of the arms 9 to 12 to the ends of the armature. This construction not only facilitates the rigid holding of the voice coils as just described, but it is also advisable from an 30 operating standpoint to prevent the return of flux through the air-gap between the coils and the adjacent arms, whereby the efficiency of the motor might be cut down. To hold the coils against the pole pieces for 35 this reason, and to secure the positive engagement aforesaid, spring members 42 shown in Figures 17 and 18 are provided, which do not need special description. Their use is illustrated clearly in Figures 40 21 and 25.

50 Modifications may be made in our invention without departing from the spirit thereof, and our invention is not restricted to the specific commercial embodiment herein described.

Having thus described our invention, what we claim as new and desire to secure by Letters Patent, is:—

1. In a loud speaker motor, members comprising a field assembly providing a magnetic circuit, and an armature member assembly comprising means forming a magnetic circuit, the members forming said circuits lying essentially in different planes.

65 2. In a loud speaker motor, a field as-

sembly providing a magnetic circuit in which interspaced pole pieces, an armature lying between said pole pieces, and a saturated magnetic connection between said armature and each of said pole pieces. 70

3. In a loud speaker motor, a field assembly comprising interspaced pole pieces, an armature having a central portion located between said pole pieces, a saturated magnetic connection between one end of said armature and one of said pole pieces and a saturated magnetic connection between the other end of said armature and said other pole piece. 75

4. In a loud speaker motor, a field assembly having interspaced portions of opposite polarity, an armature of strip form having its central portion located between said field portions, and saturated magnetic arms external of said field structure connecting 80 the ends of said armature to said portions of opposite polarity. 85

5. In a loud speaker motor, a field assembly comprising interspaced pole pieces of opposite polarity, members providing saturated by-pass paths for a portion of the field flux, said members magnetically connecting said pole pieces at opposite sides, an armature having its central portion located between said pole pieces, said armature magnetically connected to said saturated by-pass members. 90 95

6. In a loud speaker motor, a field assembly comprising a magnetic yoke and interspaced pole pieces, an armature having its central portion located between said pole pieces, and magnetic connections between the ends of said armature and said pole pieces, said connections being of a size small enough to be kept substantially in a saturated condition by said field flux. 100 105

7. In a loud speaker motor, a field assembly comprising a magnetic yoke and interspaced pole pieces, an armature of strip form extending between said pole pieces 110 and saturated magnetic connections of strip form between the ends of said armature and said pole pieces, said connections in strip form being magnetically saturated and having less capacity to carry magnetic 115 flux than the component parts of said field assembly.

8. In a loud speaker motor, a field assembly providing a magnetic circuit and interspaced pole pieces, an armature assembly 120 comprising an armature and saturated magnetic connections between said armature and said pole pieces, whereby a second magnetic circuit is formed in a different plane and coils on said armature at either side of said 125 pole pieces.

9. In a loud speaker motor, a substantially C-shaped field core construction, an armature of strip form extending transversely between the opposed portions of said C, 130

saturated magnetic connections between the outer ends of said armature and the opposed portions of said **C**, voice coils surrounding said armature, and a field coil on a portion 5 of said **C**.

10. In a loud speaker motor, a substantially **C**-shaped field core construction, an armature of strip form extending transversely between the opposed portions of said 10 **C**, magnetic connections between the outer ends of said armature and the opposed portions of said **C**, voice coils surrounding said armature, said connections being small enough in area to be kept substantially saturated 15 by the flux in said **C**.

11. In a loud speaker motor, members comprising a field assembly providing a magnetic circuit, and an armature member providing a magnetic circuit, the members 20 forming said circuits lying essentially in different planes, the armature lying essentially at the center of a balanced magnetic bridge circuit.

12. In a loud speaker motor, a **C**-shaped 25 field core, a field coil on the back of said core, an armature of strip form transverse to said field core and lying with its central portion between opposed portions of said **C**, a drive rod attached to said armature and 30 passing through a perforation in one of said opposed portions, and magnetic connections between the ends of said armature and said opposed portions.

13. In a loud speaker motor, a **C**-shaped 35 field core, a field coil on the back of said core, an armature of strip form transverse to said field core and lying with its central portion between opposed portions of said **C**, a drive rod attached to said armature and 40 passing through a perforation in one of said opposed portions, and voice coils surrounding said armature and located between said opposed portions and the outer ends of said armature, and magnetic connections between 45 the outer ends of said armature and said opposed portions.

14. In a loud speaker motor, a field assembly comprising interspaced pole pieces, an armature of the reed type having its free 50 end located between said pole pieces, and saturated magnetic connections external of said field assembly between the other end of said armature and each of said pole pieces.

15. In a loud speaker motor, a field assembly 55 having interspaced portions of opposite polarity, and an armature of strip form having a portion located between said field portions, and saturated magnetic arms externally of said field structure connecting an 60 end of said armature to said portions of opposite polarity.
